[57] CLAIM

The ornamental design for an automobile tire, as shown and described.

DESCRIPTION

FIG. 1 is a perspective view of an automobile tire showing our new design, it being understood that the tread design is repeated uniformly throughout the circumference of the tire.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a perspective view of an automobile tire showing a second embodiment of our new design, it being understood that the tread design is repeated uniformly throughout the circumference of the tire;

FIG. 7 is a front elevational view FIG. 6;

FIG. 8 is a rear elevational view FIG. 6;

FIG. 9 is a right side elevational view FIG. 6; and,

FIG. 10 is a left side elevational view FIG. 6.

*FIG. 1**FIG. 2**FIG. 3**FIG. 4**FIG. 5**FIG. 6**FIG. 7**FIG. 8**FIG. 9**FIG. 10*
